[57] CLAIM

I claim the ornamental design for a portable urine holding device, as shown and described.

DESCRIPTION

FIG. 1 is a right perspective view of a portable urine holding device showing my new design;
FIG. 2 is a right side elevational view thereof, the undisclosed left side being a mirror image;
FIG. 3 is a front end view thereof;
FIG. 4 is a back end view thereof;
FIG. 5 is a top view thereof; and,
FIG. 6 is a bottom view thereof.
